UNITED STATES PATENT OFFICE.

JOSEPH J. BLACK, OF DAYTON, OHIO, ASSIGNOR TO THE MASTER TIRE AND RUBBER COMPANY, OF DAYTON, OHIO, A CORPORATION OF OHIO.

DESIGN FOR A TIRE.

57,307.

Specification for Design.

Patented Mar. 15, 1921.

Application filed March 22, 1920. Serial No. 367,878. Term of patent 14 years.

To all whom it may concern:

Be it known that I, JOSEPH J. BLACK, a citizen of the United States, residing at Dayton, in the county of Montgomery and State of Ohio, have invented a new, original, and ornamental Design for Tires, of which the following is a specification, reference being had to the accompanying drawings, forming part thereof.

Figure 1 is an edge view of a tire showing my design; and

Fig. 2 is a cross sectional view.

I claim:—

The ornamental design for a tire as shown.

JOSEPH J. BLACK.
